UNITED STATES PATENT OFFICE

ERNEST S. JOHNSON, OF WEBSTER CITY, IOWA, ASSIGNOR TO KNAAPP-MONARCH COMPANY, OF ST. LOUIS, MISSOURI, A CORPORATION OF MISSOURI

STOPPER OR CLOSURE FOR RECEPTACLES

Application filed September 11, 1926. Serial No. 134,794.

This invention relates to a stopper or closure for receptacles, more particularly of the insulated type, as for example, those jugs and other receptacles in common use 5 for keeping foods or liquids hot or cold.

Among the objects of this invention is to provide a stopper or closure of the class referred to above having a smaller stopper incorporated therein, whereby upon removal 10 of the latter liquid contents of the container can be poured therefrom without the necessity of removing the entire closure.

A further object of this invention is to provide a closure or stopper of simplified 15 and more economical construction, of increased efficiency and ease in manipulation.

A further object is to provide a stopper or closure, insulated at that portion which enters the opening of the receptacle, and of 20 such construction that its more important parts can be readily stamped out by dies and assembled quickly and easily.

A still further object is the provision of a 25 gasket of rubber, or the like, that will seat itself against the upper edge of the neck of the container to which the stopper or closure is applied.

A further object is to provide a stopper or closure so constructed as to reduce to the 30 minimum the change in heat condition of the contents of the receptacle when a portion of the contents is being removed therefrom.

Further objects, advantages and capabilities will later more fully appear.

My invention further resides in the combination, construction and arrangement of 35 parts illustrated in the accompanying drawings, and while I have shown therein a preferred embodiment I wish it to be understood that the same is susceptible of modification and change without departing from the spirit of my invention.

In the drawings:—

Fig. 1 is a fragmentary elevational view 45 of the upper portion of a heat insulated container to which my improved stopper is applied, the cup being partly broken away for the sake of clearness.

Fig. 2 is a bottom plan view of my improved stopper or closure looking upwardly

at the same when in the position shown in Fig. 1.

Fig. 3 is a vertical transverse central sectional view taken on the line 3—3 of Fig. 2.

Fig. 4 is a view similar to Fig. 2, but 55 showing a modification in the arrangement of the rubber gasket.

Fig. 5 is a vertical transverse sectional view on the line 5—5 of Fig. 4.

As will be seen in the drawings, my improved stopper or closure is applied to a receptacle 1 of the nature of a heat insulated jug, or the like. I do not wish, however, to be limited to the particular kind of receptacle to which this is applied, as my invention is 60 broad enough to be used in connection with any receptacle where such a stopper or closure is desired. More in detail my improved stopper comprises the main body member 2, having depending cylindrical sides 3, in which 65 are rolled or otherwise suitably formed threads 4, to be threaded on to similar threads formed in the upstanding outer portion of the neck in the receptacle 1. A suitable bead, or the like, 5, is circumferentially formed on 70 the lower edge of the depending cylindrical walls 3.

Centrally formed in the top of the body member 2 is an opening 6 surrounded by the 75 upstanding flange 7 formed integrally with the top of the member 2. An inner hollow member 8 is arranged in inverted position, as shown in Fig. 3, within body member 2. Projecting upwardly from member 8 is the 80 cone-shaped portion 9, terminating in a cylindrical upstanding member 10, which when inserted through opening 6 has its free edge 11 85 spun or otherwise suitably beaded down over the upstanding flange 7, which latter may, if desired, have the turned back outer portion 12. In other words, the cylindrical extension 10 of member 8 is passed through the 90 central opening in the body member 2, and the flange of the latter and the free edge of the cylindrical member 10 are crimped over so as to form a bead, or the like, as shown in Figs. 3 and 5. Any suitable arrangement of the 95 parts in this connection would suffice, the main idea being to firmly secure the upstanding cylindrical extension of member 8 within 100

body member 2, so that the same will be securely fastened together and present a pleasing appearance.

Hollow member 8 is also formed with the upstanding cylindrical wall 13, which may or may not as desired be formed at its upper free edge with the outstanding flange 14. In the form shown in Figs. 2 and 3 a gasket 15 of rubber, fibre, or other insulating material, is positioned and secured between the upper edge of cylindrical wall 13, and the adjacent top portion of body member 2. This gasket in this form of the invention is, of course, placed in position, after which the hollow member 8 is secured, as shown in Fig. 3, to clamp the gasket 15 between these parts.

In Figs. 4 and 5 the gasket is not positioned prior to assembling the parts as in Fig. 3, but after hollow member 8 has been secured in position within body member 2. In the latter form the gasket 15 is applied to the outer circumference of wall 13 after the stopper or closure has been formed, and may, as will be apparent, be removed or returned to position as desired. Also in the form shown in Fig. 3 an additional gasket, as shown in Fig. 5, may be applied around the cylindrical wall 13 at any time the gasket 15 shows signs of deterioration.

In order to prevent the necessity of removing the entire stopper, I have provided to fit within the opening formed by the upstanding cylindrical extension 10 a cork member 16 having a suitable metal top crimped around the upper edges of the cork, as shown at 17. This cork 16 of smaller diameter is of great convenience when it is desired to pour ice cold liquids from the jug or receptacle without having the cracked ice also flow out with the liquid. This provision of a smaller inner cork also increases the efficiency of the jug or receptacle, as it prevents the atmospheric air from flowing into the jug or receptacle to decrease its insulating efficiency.

The cylindrical wall 13 of hollow member 8 is of an external diameter substantially the same or slightly less than the internal diameter of the neck of the jug or receptacle, so that when the stopper or closure is applied to the receptacle the hollow member 8 will form the stopper for said neck. As is readily seen in the drawing this construction affords the dead air space 18 between the hollow member 8, which space may or may not, as desired, be filled with ground cork or other suitable insulating material, as desired. Such filling is not necessary as the dead air space will itself function as an efficient insulation. A cup 19 is also provided to be inverted and fit snugly over the threads 4 when the stopper is in place, thus rendering available for drinking, or other purposes, the cup 19 when desired.

Having now described my invention what I claim is:

65 1. In a stopper a main cup-shaped body

portion having a central opening through its upper face and a threaded circumferential skirt, a hollow member of smaller external diameter than the diameter of said skirt, said hollow member being formed with a central upstanding tubular extension of greater height than the depth of the hollow in said hollow member, said tubular extension passing through the said opening and being secured therein, the outer free edge of the hollow member being secured with relation to the inner face of the main body portion when the tubular extension is secured in the opening so as to form an insulated stopper within said skirt, and a secondary stopper removably fitted in said tubular portion of the hollow member.

2. In a stopper a main body portion having a central opening formed with an upstanding marginal flange, a hollow member formed with an upstanding tube snugly extending through said opening, the upper free edge of the tube being upset and beaded around said marginal flange to form a tight connection between the hollow member and the main body portion, so that the main body portion has extending inwardly therefrom an insulated member to fit within the neck of the receptacle.

3. In a stopper a main body portion having a central opening formed with an upstanding marginal flange, a hollow member formed with an upstanding tube snugly extending through said opening, the upper free edge of the tube being upset and beaded around said marginal flange to form a tight connection between the hollow member and the main body portion, so that the main body portion has extending inwardly therefrom an insulated member to fit within the neck of the receptacle to receive said stopper, the said tube forming a passage entirely through said stopper, and a secondary stopper removably fitting in said tube.

4. In a stopper of the class described a cup-shaped main body portion formed of sheet metal adapted to fit over and threadedly engage a neck of a receptacle, an inverted sheet-metal hollow member of a size to fit the neck of the receptacle and secured to the inner face of the main body portion, the air space within said hollow member serving as an insulating means for the neck of the receptacle.

5. In a stopper of the class described a cup-shaped main body portion formed of a sheet metal, an inverted sheet-metal hollow member of a size to fit the neck of a receptacle and secured to the inner face of the main body portion, the air space within said hollow member serving as an insulating means for the neck of the receptacle, and a cup fitted over and spaced from said main body portion for providing a further insulating means for the neck of the receptacle.

6. In a stopper of the class described a cup-

shaped main body portion formed of sheet metal adapted to fit over and threadedly engage the neck of a receptacle, an inverted sheet-metal hollow member of a size to fit the neck of the receptacle and secured to the inner face of the main body portion, the air space within said hollow member serving as an insulating means for the neck of the receptacle, a walled passage extending through said hollow member and said main body portion, and a secondary stopper removably fitting in said passage.

7. In combination with an insulated jug or container having an upstanding neck providing a large opening and formed with an external thread, a stopper having a flange internally threaded for detachable engagement with the neck and having a hollow portion secured thereto and adapted to extend into the opening formed by the neck, said latter portion having an opening therethrough registering with an opening in the top wall of said stopper, and a smaller stopper removably inserted in said opening.

15 8. In combination with an insulated jug or container having a relatively large opening, a stopper detachably connected to said container and having an insulated portion adapted to project into said opening, said insulated portion having an opening therethrough registering with an opening in the top wall of said stopper, a smaller stopper detachably inserted in said opening and a hollow cap enclosing said first mentioned 30 stopper and forming an air space about said second stopper.

9. An insulated jug or container having an upstanding neck formed with external threads, a stopper of sheet metal having a threaded circumferential flange screwing onto the neck, said stopper having an insulated portion projecting into the neck of the container and formed with an opening therethrough registering with an opening in 45 the top wall of said stopper, a second stopper closing said opening, and a sheet metal cup adapted to engage the threads of the external surface of the flange of the first mentioned stopper to enclose its upper portion and to 50 form an air space about the second stopper.

10. A stopper for an insulated receptacle, comprising a body portion provided with an opening and flanges adapted to fit over and engage said receptacle, a hollow depending member secured to said body portion and provided with a central tubular part protruding through said opening, and a stopper in said tubular part.

11. A stopper for an insulated receptacle, 60 comprising a body portion provided with an opening and flanges, said flanges adapted to threadedly engage the walls of said receptacle and close an opening thereof, a hollow member secured to said body portion, said member 65 having a tubular part protruding through

said opening and secured to said body portion, and a stopper in said tubular part.

12. A stopper for an insulated receptacle, comprising a body portion, said body portion having a central flanged part defining an opening, an insulating member secured to said body portion, said member having a central tubular portion protruding through said opening and secured to said flanged part, and a stopper in said tubular portion.

13. A stopper for an insulated receptacle, comprising a body portion, said body portion having a central flanged part defining an opening, an insulating member secured to said body portion, said member having a central tubular portion protruding through said opening, the end of the tubular portion being beaded for engaging said flanged part, and a stopper in said tubular portion.

14. A closure device for an insulated receptacle, comprising a stopper adapted to threadedly engage the walls of said receptacle and to close an opening thereof, said stopper provided with an insulating means and a passage therein, means for closing said passage, and a second stopper threadedly engaging said first stopper and providing an air space thereabove.

15. A closure device for an insulated receptacle, comprising a stopper having an opening therethrough and provided with threaded flanges engaging the walls of said receptacle, means removably inserted in said opening, and a second stopper threadedly engaging said flanges of said first stopper, said second stopper being spaced from said first stopper for providing an air space therebetween.

16. A closure device for an insulated receptacle, comprising a stopper having threaded flanges engaging the walls of said receptacle, an insulating member secured to said stopper and adapted to extend into an opening of said receptacle, said stopper having a central tubular opening normally closed, and a second stopper threadedly engaging the flanges of said first stopper and having parts spaced from said first stopper to provide an air space therebetween.

In witness whereof, I hereunto subscribe my name to this specification.

ERNEST S. JOHNSON.
